UNITED STATES PATENT OFFICE

149,291

DESIGN FOR A THEATRE

Carl G. Moeller, Los Angeles, Calif., assignor to
Fox West Coast Theatres Corporation, Los Angeles, Calif., a corporation of Delaware

Application August 13, 1946, Serial No. 132,471

Term of patent 14 years

(Cl. D13—1)

To all whom it may concern:

Be it known that I, Carl G. Moeller, a citizen of the United States, residing at Los Angeles, in the county of Los Angeles, State of California, have invented a new, original, and ornamental Design for a Theatre, of which the following is a specification, reference being had to the accompanying drawings, forming a part thereof.

Fig. 1 is a front perspective view of a theatre showing my new design;

Fig. 2 is a top plan view; and

Fig. 3 is a front elevational view thereof.

The side of the theatre opposite the side shown with a paneled appearance is identical therewith in size, shape and appearance, while the rear end side opposite the side corresponding to the entrance is essentially a plain surface.

I claim:

The ornamental design for a theatre, as shown and described.

CARL G. MOELLER.
